UNITED STATES PATENT OFFICE.

JOSEPH S. BLINN, OF NEW HAVEN, CONNECTICUT, ASSIGNOR TO THE SCOVILLE MANUFACTURING COMPANY, OF WATERBURY, CONNECTICUT.

DESIGN FOR A CAMPAIGN-BADGE.

SPECIFICATION forming part of Design No. 25,453, dated May 5, 1896.

Application filed March 24, 1896. Serial No. 584,701. Term of patent 3½ years.

To all whom it may concern:

Be it known that I, JOSEPH S. BLINN, of New Haven, in the county of New Haven and State of Connecticut, have invented a new 5 Design for a Campaign-Badge; and I do hereby declare the following, when taken in connection with the accompanying drawings, to be a full, clear, and exact description of the same, and which said drawings constitute part 10 of this specification, and represent, in—

This invention relates to a design for campaign-badges; and the design consists in the 15 ornamentation herein described, and shown in the accompanying illustrations.

As herein shown, the badge is in the form of a button, the face of which is ornamented by the representation of a freight-car loaded with gold bullion, above which floats a long streamer.

I claim—

A design for a campaign-badge as herein shown and described.

In testimony whereof I have signed this specification in the presence of two subscribing witnesses.

JOSEPH S. BLINN.
